(57) **CLAIM**

The ornamental design for a buckle keeper, as shown and described.

DESCRIPTION

FIG. 1 is a top perspective view of a first embodiment of a buckle keeper in its open position showing my new design; FIG. 2 is a front view of a first embodiment of a buckle keeper in its open position;

FIG. 3 is a rear view of a first embodiment of a buckle keeper in its open position;

FIG. 4 is a right side view of a first embodiment of a buckle keeper in its open position;

FIG. 5 is a left side view of a first embodiment of a buckle keeper in its open position;

FIG. 6 is a bottom view of a first embodiment of a buckle keeper in its open position;

FIG. 7 is a top view of a first embodiment of a buckle keeper in its open position;

FIG. 8 is a front perspective view of the buckle keeper of FIG. 1 in its open position being placed over the buckle of a duty belt;

FIG. 9 is a front perspective view of the buckle keeper of FIG. 1 in its closed position over the buckle of a duty belt;

FIG. 10 is a top perspective view of a second embodiment of a buckle keeper in its open position showing my new design; FIG. 11 is a front view of a second embodiment of a buckle keeper in its open position;

FIG. 12 is a rear view of a second embodiment of a buckle keeper in its open position;

FIG. 13 is a right side view of a second embodiment of a buckle keeper in its open position;

FIG. 14 is a left side view of a second embodiment of a buckle keeper in its open position;

FIG. 15 is a bottom view of a second embodiment of a buckle keeper in its open position;

FIG. 16 is a top view of a second embodiment of a buckle keeper in its open position;

FIG. 17 is a front perspective view of the buckle keeper of FIG. 10 in its closed position over the buckle of a duty belt;

FIG. 18 is a top perspective view of the first embodiment of a buckle keeper in its open position showing my new design. The badge shown on the front of the design being for illustrative purposes only and forming no part of the claimed design;

FIG. 19 is a front view of the first embodiment of a buckle keeper bearing a badge in its open position;

FIG. 20 is a rear view of the first embodiment of a buckle keeper bearing a badge in its open position;

FIG. 21 is a right side view of the first embodiment of a buckle keeper bearing a badge in its open position;

FIG. 22 is a left side view of the first embodiment of a buckle keeper bearing a badge in its open position;

FIG. 23 is a bottom view of the first embodiment of a buckle keeper bearing a badge in its open position;

FIG. 24 is a top view of the first embodiment of a buckle keeper bearing a badge in its open position;

FIG. 25 is a front perspective view of the buckle keeper of FIG. 18 in its closed position over the buckle of a duty belt;

FIG. 26 is a top perspective view of a third embodiment of a buckle keeper in its open position showing my new design; FIG. 27 is a front view of a third embodiment of a buckle keeper in its open position;

FIG. 28 is a rear view of a third embodiment of a buckle keeper in its open position;

FIG. 29 is a right side view of a third embodiment of a buckle keeper in its open position;

FIG. 30 is a left side view of a third embodiment of a buckle keeper in its open position;

FIG. 31 is a bottom view of a third embodiment of a buckle keeper in its open position; and,

FIG. 32 is a top view of a third embodiment of a buckle keeper in its open position.

Left side views not shown are mirror images of right side views. Any broken lines illustrative of environmental structure in the drawings are not part of the design sought to be patented.
